UNITED STATES PATENT OFFICE.

GEORGE NORMAN SANNESS, OF CHICAGO, ILLINOIS.

COMBINATION ASH RECEIVER AND CIGAR LIGHTER.

Application filed July 26, 1924. Serial No. 728,293.

To all whom it may concern:

Be it known that I, GEORGE NORMAN SANNESS, a citizen of the United States, and a resident of the city of Chicago, county of Cook and State of Illinois, have invented a certain new and useful improvement in a Combination Ash Receiver and Cigar Lighter, of which the following is a specification.

My invention relates to a combination ash receiver and cigar lighter, and has for its paramount object the provision of an improved construction of this character which will be highly serviceable in use.

A further object of my invention is the provision of a simply constructed device of the character specified, capable of holding a considerable quantity of fuel and equipped with a main ash receiving reservoir, and which in addition has a freely removable hood or cover containing an ash tray adapted to be tilted for discharge of its contents into the main ash receiving reservoir.

Other objects will appear hereinafter.

The invention consists in the combinations and arrangements of parts hereinafter described and claimed.

The invention will be best understood by reference to the accompanying drawings forming a part of this specification, and in which,

Fig. 1 is a top plan view of my improved device;

Fig. 2 is a vertical section taken on the line 2-2 of Fig. 1; and

Fig. 3 is a similar section taken on the line 3-3 of Fig. 2.

In accordance with the embodiment exemplified in the accompanying drawing, my improved device includes two receptacles or shells 4 and 5, supported one within the other, the receptacle designated as 4 being the inner receptacle and the receptacle designated as 5 being the outer one, both receptacles preferably being made in the square form shown. These receptacles have open tops, and the inner receptacle 4, which is intended to serve as an ash containing reservoir, is supported within the outer receptacle 5, in spaced relation thereto, by means of spacing blocks 6, held by rivets 7, which are passed through the walls of the receptacles 4 and 5. The space 8 between the walls of the receptacles 4 and 5 is intended to be used as a reservoir for holding fuel, preferably alcohol.

The fuel reservoir 8, thus formed, is closed at the top by applying upon the top ends of the receptacles 4 and 5 a square plate 9, provided with a fuel inlet 10 and an opening 11 in which is seated a lighting device presently to be explained. The plate 9 is preferably secured upon the top edges of the receptacles by soldering or welding it thereon. The fuel opening 10 is provided with a fuel receiving mouth or sleeve 12, in which is fitted a removable plug 13, preferably made of cork. In the opening 11 is fitted a tube 14 adapted to carry a wick 15, the said tube being of a length to extend an appreciable distance into the fuel chamber 8, and the wick being extended downwardly beyond the end of said tube in order to reach the bottom region of the fuel reservoir.

16 represents a hood or cover, also made of square form as shown and being of sufficient dimensions to incase the outer receptacle 5, as clearly shown in Figs. 2 and 3, this hood or cover being open at the bottom but having a top 17 in which is provided a central circular aperture 18. The top 17 of the hood also has a circular aperture 19 through which the tube 14 may be projected when the hood is applied so that the wick 15 carried by this tube may be available from the outside of the structure as means of lighting cigars, cigarettes and pipes. The central aperture 18 is normally closed by an ash receiving tray 20, having a dish-shaped bottom 21 and a circular rim 22 which is curled upon itself in order to snugly fit within the aperture 18, as shown. This ash receiving tray is hingedly engaged at 23 with the top 17, this hinged engagement being at the underside of said top so that the tray will swing downwardly into the ash receiving receptacle 4 and discharge thereto. Opposite the hinge 23 the tray 20 has a projecting lug 24 to which is attached the end of a chain 25 that is passed upwardly through an aperture 26 in the top 17. The chain 25 is of such length that it will extend downwardly over the outer receptacle 5 and it is provided with a ball or weight 26 intended to counterbalance the ash tray 20, holding the latter properly seated in the aperture 18. When it is desired to discharge ashes from the tray 20 into the receptacle 4, it is only necessary to lift up the chain 25 permitting it to be drawn downwardly through the aperture 26, so that the tray will swing by gravity into discharging position. Obviously, when it is

desired to close the aperture 18 the chain 25 is drawn upwardly through the aperture 26 and the weighted end of the chain permitted to drop over the side of the outer receptacle 5.

While I have illustrated and described the preferred form of construction for carrying my invention into effect, this is capable of variation and modification without departing from the spirit of the invention. I therefore, do not wish to be limited to the precise details of construction set forth, but desire to avail myself of such variations and modifications as come within the scope of the appended claims.

Having described my invention, what I claim as new and desire to secure by Letters Patent is:

1. A device of the class described including two receptacles arranged one within the other in spaced relation and providing a fuel chamber between the walls thereof, and a hood member removably incasing said receptacles and carrying a tray member adapted to discharge into the inner one of said receptacles, substantially as described.

2. A device of the class described including corresponding receptacles arranged one within the other, spacer members supporting the inner receptacle from the outer receptacle and providing a fuel chamber therebetween, and a hood member removably incasing said receptacles and carrying a tray member adapted to discharge into said inner receptacle, substantially as described.

3. A device of the class described including two receptacles arranged one within the other in spaced relation and providing a fuel chamber therebetween, a hood member incasing said receptacles and having a top opening, and a tray member adapted to discharge into the inner one of said receptacles hinged to said hood member and normally closing said top opening, substantially as described.

4. A device of the class described including an outer receptacle, a corresponding inner receptacle supported in spaced relation thereto and providing a fuel reservoir between said receptacles, and a wicked device associated with said reservoir, substantially as described.

5. A device of the class described including outer and inner receptacles, spacer members supporting the inner receptacle from the outer receptacle to provide a fuel reservoir around the inner receptacle, a sealing member between said receptacles, and a wicked device associated with said sealing member, substantially as described.

6. A device of the class described including outer and inner receptacles, spacer members supporting the inner receptacle from the outer receptacle to provide a fuel reservoir around the inner receptacle, a wicked device projecting from said reservoir, a hood member placed over and incasing said receptacles and having an opening through which said wicked device passes, substantially as described.

7. A device of the class described including two receptacles arranged one within the other and having spaced side, end and bottom walls providing a fuel reservoir between said receptacles, a wicked device projecting forwardly from said reservoir, a hood member placed over and incasing said receptacles and having an opening for the projection therethrough of said wicked device and a tray member adapted to discharge into said inner receptacle carried by the hood member, substantially as described.

In testimony whereof I have signed my name to this specification in the presence of two subscribing witnesses.

GEORGE NORMAN SANNESS.
